Application November 17, 1948, Serial No. 60,581

5 Claims. (Cl. 217—31)

1

This invention relates in general to partition structures and assemblages which are used in portable boxes or cases to provide individual cells or compartments for bottles, jars, and the like, containing beverages or other packaged goods.

The invention deals, more particularly, with improvements in the construction and arrangement of the members of such a partition in a manner which provides for relatively greater strength and increased durability of the partitions and which otherwise involves important savings in the assembly of the partitions and other costs of manufacture.

Various types of partitions made of paperboard, cardboard or the like, consist of a honeycomb arrangement provided by sets of partition members or strips extending substantially at right angles to each other and formed with slots along their adjacent edges by which the sets of strips are secured together in intersecting relation in the completed partition. The slotted edge portions of the paperboard or cardboard strips are necessarily weak and fragile and subject to tearing all too easily in the areas adjacent the slots. Such partitions, therefore, have only a short period of satisfactory usage before they are so torn and mutilated that they are unsatisfactory and must be replaced. While the usual partitions are not expensive, they amount to a sizeable cost when used in great quantities, as by distributors of bottled beverages, for example, and consequently important savings are involved in the provision of a partition structure wherein the replacement requirements are minimized in any material way.

A primary object of the invention is to provide an improved paperboard or cardboard partition structure of the kind described in which the strips comprising one set of partition members are wider than the other set and are provided with intermediate cutout areas which receive the other set of partition strips in an arrangement wherein each of all the strips is formed on both edges with continuous, imperforate, unbroken longitudinal edge portions which are relatively strong and durable and capable of greater wear and resistance against forces which otherwise would tend to tear or mutilate the partition strips; the arrangement otherwise is such that the cutout areas in the wider strips include pairs of cooperating locking tongues or flaps that are received in spaced slots in the narrower strips to secure the strips together at their intersections in interlocked joints which prevent displacement of the strips in the completed partition either

when distended for use or when folded in flatwise condition for shipping, etc.

Another object of the invention is to provide a partition structure of this character in which the cutouts in the wider strips comprise a pair of oppositely extending locking tongues which are received in spaced slots in the narrower strips in a manner whereby said oppositely extending tongues provide an equal and balanced locking action in the interlocked joint of the intersecting strips.

A further object of the invention is to provide a partition structure, as aforesaid, in which the oppositely extending tongues of the interlocked joints are adapted to permit a slight expansion in the joints which facilitates folding of the partition structure and otherwise provides for suitable enlargement of the partition cells to receive bottles of slightly larger size when necessary.

An additional object of the invention is to provide an improved partition structure having the foregoing advantages and new features of construction and which is readily adapted for mass production manufacture by existing machinery and equipment.

Further objects and advantages, and other new and useful features in the construction, arrangement and general combination of parts of the invention will be apparent as the following description proceeds with reference to the accompanying drawings, for purposes of illustration but not of limitation, in which like reference characters designate like elements throughout, and in which:

Fig. 1 is a perspective view illustrating a partition structure in accordance with the invention as provided in a conventional bottle carrying case or box, represented in dotted lines;

Fig. 2 is a fragmentary perspective view illustrating one of the joints of the intersecting partition members and showing the details of the interlocking elements of the joint in accordance with the invention;

Fig. 3 is a perspective view showing portions of a pair of partition members in position to be assembled and illustrating the formation of the cutout and slotted areas therein to provide the interlocked joint shown in Fig. 2;

Fig. 4 is an edge elevational view of portions of a pair of intersecting partition members in the process of assembly and shows the disposition of the locking tongues in the joint as the partition members are advanced to assembled relation;

Fig. 5 is a sectional view through the inter-

10

15 joints are adapted to permit a slight expansion in the joints which facilitates folding of the partition structure and otherwise provides for suitable enlargement of the partition cells to receive bottles of slightly larger size when necessary.

20 An additional object of the invention is to provide an improved partition structure having the foregoing advantages and new features of construction and which is readily adapted for mass production manufacture by existing machinery and equipment.

25 Further objects and advantages, and other new and useful features in the construction, arrangement and general combination of parts of the invention will be apparent as the following description proceeds with reference to the accompanying drawings, for purposes of illustration but not of limitation, in which like reference characters designate like elements throughout, and in which:

30 Fig. 1 is a perspective view illustrating a partition structure in accordance with the invention as provided in a conventional bottle carrying case or box, represented in dotted lines;

35 Fig. 2 is a fragmentary perspective view illustrating one of the joints of the intersecting partition members and showing the details of the interlocking elements of the joint in accordance with the invention;

40 Fig. 3 is a perspective view showing portions of a pair of partition members in position to be assembled and illustrating the formation of the cutout and slotted areas therein to provide the interlocked joint shown in Fig. 2;

45 Fig. 4 is an edge elevational view of portions of a pair of intersecting partition members in the process of assembly and shows the disposition of the locking tongues in the joint as the partition members are advanced to assembled relation;

50 Fig. 5 is a sectional view through the inter-

55

locked joint shown in Fig. 2 as taken on line 5—5 looking in the direction of the arrows; and,

Fig. 6 is a sectional view of the interlocked joint as seen along line 6—6 of Fig. 5 looking in the direction of the arrows.

Referring now, more particularly, to the drawings, the invention is shown, for illustrative purposes only, as provided in a partition structure within a box or case for shipping or transporting bottles, or the like. In the present example, the partition structure, designated generally P in Fig. 1, is shown as provided for carrying twelve bottles but it will be understood that the principles of the invention are equally applicable to the construction of any similar or related type of partition for accommodating any other selected number of bottles, jars, and like articles made of glass, plastics and other frangible and brittle materials. The bottles and other articles preferably have a snug fit within the individual cells or compartments of the partition and by utilizing a soft porous material to provide the partitions, the bottles are cushioned and spaced slightly apart from each other and thereby effectively protected against breakage during shipping and handling. The partition structure P is illustrated in connection with a well known type of box or bottle carrying case B, represented in dotted lines in Fig. 1, but, of course, the partition is readily provided in any other size or form for any other type of box or case, particularly existing boxes and cases of standard and conventional design.

The partition members in the form of strips or boards are provided from any suitable material such as cardboard, paperboard, fibreboard, or the like, the thickness of which is selected according to service requirements and the size and type of bottles or other articles with which the partition is to be used. The partition structure comprises, in general, two sets of partition members or strips 10 and 20, respectively, the set of partition members or strips 10 being wider than the other set of strips 20. In the present example, the wider strips 10 are shown extending transversely of the box but this is merely a matter of choice or expediency inasmuch as the partition in any form may be provided just as well with said wider strips 10 extending lengthwise of the box and the narrower strips 20 disposed transversely thereof.

As best seen in Fig. 3, each of the wider strips 10 is provided with vertical cutout or slotted areas 11 at predetermined spaced points along the length thereof as necessary to provide the required number and size of cells to be contained in the partition structure according to the number and size of bottles or other articles the partition is to accommodate. The cutout areas 11 are formed in intermediate spaced relation to the longitudinal edges of the strip so that said strip comprises relatively strong, continuous imperforate and unbroken longitudinal edge portions 12 which provide maximum resistance against any force which might tend to tear, rupture or mutilate the strips.

The cutout areas 11 are so punched as to provide a pair of similar tongues 14 extending in opposite directions and spaced apart by an intermediate slot 15 and end slots 16 adjacent the longitudinal edge portions 12. The junction of each tongue 14 with the body of the strip is preferably scored as represented by broken lines 17 or otherwise conditioned to facilitate bending of both tongues in the same direction as illustrated in Fig. 4. Preferably the tongues 14 are provided with bevelled side edges tapering inwardly toward

their free ends while the extremities of said tongues are spaced only slightly from the adjacent body portions of the strip by thin slits or knife cuts as best seen in Fig. 5.

5 The narrower strips 20 are of a height approximating the length of the cutout areas 11 in the wider strips. Each of the narrower strips 20 is provided with pairs of transverse slot-like recesses 21 in predetermined spaced relation along the length thereof according to the number and size of cells to be contained in the partition structure. The pairs of slots 21 have a size and spacing corresponding substantially to the size and spacing of the tongues 14 provided in the cutout areas of 15 the wider boards 10. However, the width of the slots 21, as shown in Fig. 6, preferably is substantially wider than the thickness of the tongues 14 so as to provide a suitable clearance by which said tongues are movably received in said spaced slots 21 in what may be termed a floating lock. By virtue of such clearance, the joints of the intersecting partition members 10, 20, are capable of yielding as necessary to accommodate bottles of slightly larger size while the completed partition otherwise is adapted to fold more readily to flatwise condition. The spaced slots 21 are formed in inwardly spaced relation to the longitudinal edges of the narrower strip 20 so that said strip comprises, likewise, continuous, imperforate and unbroken longitudinal edge portions 22 which are relatively strong and durable and capable of providing maximum resistance against any force which would tear or mutilate the same if notched or slotted along such longitudinal edges. The strip 20 is additionally strengthened by an imperforate portion 25 of the body of the strip between said spaced slots 21. The strips 20 preferably are provided on their ends with bevelled or chamfered corners 27, Fig. 3, which facilitate the initial insertion of the strips through the cutout areas 11 in the wider strips 10 in the assembly of the partition structure.

From the foregoing, it will be understood that the assembly of a partition structure in accordance with the invention is easily and quickly effected by passing a set of the narrower strips 20 through the aligned cutouts 11 in a set of the wider strips 10. The narrower strips 20 may be inserted from either end and the bevelled corners 27 thereof serve to facilitate the initial entrance thereof into the cutout areas 11 in the wider strips 10. As the leading end of a narrower strip 20 engages the tongues 14, both of said tongues bend outwardly in the same direction as seen in Fig. 4 by reason of the scoring 17. This permits the narrower strips 20 to be advanced readily through each of the aligned cutouts 11 in a set of the wider strips 10 to their final location in the partition structure in which the spaced slots 21 therein are in position to receive the tongues 14 of the associated cutouts 11 in the wider strips 10. The bevelled side edges of the tongues 14 facilitate the entrance thereof into said spaced slots 21, whereupon said tongues 14 return to their normal position in the plane of the strip 10 as shown in Figs. 2, 5 and 6. Inasmuch as the extremities of the tongues 14 are separated only by thin slits from the adjacent body portions of the strip 10, said tongues are disposed in abutting relation with substantially the full thickness of the marginal side walls of said slots 21, as seen in Fig. 5, to provide a strong and positive interlocked joint of the intersecting portions of the strips 10, 20. In this regard, a highly effective joint is provided 75 in an alternate construction comprising similar

spaced tongues at the same side of the cutout 11 and extending in the same direction. The invention fully contemplates such an alternate construction and any equivalent arrangement of tongues such as three or four or more tongues extending either in the same direction or in alternately opposite directions, as may be readily understood.

In the present preferred embodiment of the invention, the arrangement of the pairs of spaced tongues 14 in oppositely extending relation provides for a balanced and equal securing or locking action of said tongues in the spaced slots 21 in a manner whereby the narrower strips 20 are interlocked at each joint with the wider strips 10 against displacement in either direction from assembled position in the completed partition structure. In this relation, the formation of the spaced slots 21 in a width somewhat greater than the thickness of the tongues 14 provides the necessary clearance for a floating lock of said tongues in said recesses, as aforesaid, so that each cell in the partition is capable of limited expansion to accommodate slightly larger size bottles if necessary. This clearance of the tongues 14 in the spaced slots 21 and the scoring of said tongues, as along the broken lines 17, Figs. 3 and 5, provide for any required flexing of the tongues as necessary to permit the assembled partition to be easily and quickly folded into a flatwise condition for shipping or storage. Such folding of the partition to flat or collapsed condition does not release any of the various interlocked joints provided by the tongues 14 seated in the spaced slots 22, as aforesaid, and this advantageously prevents displacement of any of the strips of an assembled partition during shipping or handling in folded condition; thus, when a folded partition is distended for use, it is practically certain that each of the partition strips will be found in proper assembled position ready for insertion of the partition into a box or case without need for adjustment or other handling.

It will be appreciated that each of the strips 10, 20, in the partition, comprises an unbroken, continuous and imperforate longitudinal edge portion on both sides thereof which provides for maximum strength and resistance against tearing and mutilation incidental to the insertion and removal of bottles from the partition. Accordingly, the invention is highly advantageous in providing a partition structure that is much more durable and capable of a much longer period of satisfactory service and extended use than those partitions requiring open notches and slots on their exposed longitudinal edges which necessarily are easily subject to tearing and destruction after a short period of use and must therefore be replaced all too frequently at an entirely inordinate cost.

A further important advantage of the invention resides in the fact that the partition member are relatively simple strips or boards which may be readily manufactured from the same materials and by the same machinery heretofore employed for making similar partitions such that no additional cost is involved and important savings are possible by reason of their relatively longer period of satisfactory service and greatly minimized replacement requirements.

While the invention has been described in detail with a specific example, such example is intended as an illustration only, inasmuch as it will be apparent that other modifications in the construction, arrangement and general combination

of parts may be devised without departing from the spirit and scope of the invention. The present embodiment, therefore, is to be considered in all respects as illustrative and not restrictive, the scope of the invention being indicated by the appended claims rather than by the foregoing description, with all changes falling within the scope, meaning and range of equivalency of the claims intended to be embraced therein.

10. What is claimed and desired to be secured by United States Letters Patent is:

1. In a partition structure, a partition strip having a cutout extending transversely thereof and defining a pair of oppositely extending spaced tongues in said cutout, and a narrower partition strip extending through said cutout and provided with a pair of spaced slots receiving said pair of oppositely extending spaced tongues in an interlocked joint therewith, said cutout and said spaced slots being formed in the respective partition strips entirely within the longitudinal edges thereof so that each of said partition strips comprises continuous and imperforate portions along both of its longitudinal edges providing maximum resistance against tearing and mutilation of the partition strips.

2. A partition structure comprising a set of partition strips in parallel spaced relation and having aligned cutouts extending transversely of 30 the strips defining pairs of oppositely extending spaced tongues in said cutouts, and a narrower partition strip extending through said aligned cutouts and provided with pairs of transversely extending spaced slots receiving said pairs of oppositely extending spaced tongues in interlocked joints therewith, said cutouts and said spaced slots being formed in the respective partition strips entirely within the longitudinal edges thereof so that each of said partition strips comprises continuous and imperforate portions along 40 both of its longitudinal edges providing maximum resistance against tearing and mutilation of the partition strips.

3. In a partition structure, a partition strip 45 having a cutout extending transversely thereof and defining a pair of oppositely extending spaced tongues in said cutout, each of said tongues being scored at its junction to the strip and having its side edges bevelled inwardly toward the extremity thereof, and a narrower partition strip extending through said cutout and provided with a pair of spaced slots receiving said pair of oppositely extending spaced tongues in an interlocked joint therewith, said cutout and said spaced slots being formed in the respective partition strips entirely within the longitudinal edges thereof so that each of said partition strips comprises continuous and imperforate portions along both of its longitudinal edges providing maximum 60 resistance against tearing and mutilation of the partition strips.

4. A partition structure comprising a set of partition strips in parallel spaced relation and having aligned cutouts extending transversely of 65 the strips and defining pairs of oppositely extending spaced tongues in said cutouts, and a set of narrower partition strips extending through said aligned cutouts and provided with pairs of transversely extending spaced slots receiving said pairs of oppositely extending spaced tongues in interlocked joints therewith, said cutouts and said spaced slots being formed in the respective partition strips entirely within the longitudinal edges thereof so that each of said partition strips comprises continuous and imperforate portions along 70 75

both of its longitudinal edges providing maximum resistance against tearing and mutilation of the partition strips.

5. A partition structure comprising a set of partition strips in parallel spaced relation and having aligned cutouts extending transversely of the strips and defining pairs of oppositely extending spaced tongues in said cutouts, each of said tongues being scored at its junction to the strip and having its side edges bevelled inwardly toward the free end thereof, and a set of narrower partition strips extending through said aligned cutouts and provided with pairs of transversely extending spaced slots receiving said pairs of oppositely extending spaced tongues in interlocked joints therewith, said cutouts and said spaced slots being formed in the respective partition

strips entirely within the longitudinal edges thereof so that each of said partition strips comprises continuous and imperforate portions along both of its longitudinal edges providing maximum resistance against tearing and mutilation of the partition strips.
